UNITED STATES PATENT OFFICE

CHARLES E. BEYER, OF ROSAMOND, CALIFORNIA

LIQUID FUEL BURNER

Application filed December 4, 1929. Serial No. 411,632.

This invention relates to a liquid fuel burner, which is particularly adapted to be positioned in the fire box of a stove, boiler, heating stove, or similar construction.

5 An object of the invention is to provide a cheap, simple, and durable construction, which will insure safety and which will have an efficient and simple operation.

Another object of the invention is to provide an oil burner which will operate efficiently upon all grades of fuel and which is so designed that the supply pipe delivering fuel to the burner will not be subjected to excessive heat, causing the supply pipe to be kept comparatively clean, without requiring cleaning at regular intervals because of the carbon deposited therein. The improved burner is advantageous in that it may be successfully employed when burning wood, or similar fuel, and oil simultaneously, thus enabling the user to economize on oil fuel when wood or other fuel is plentiful.

20 A further object of the invention is to provide an oil burner which can be supplied with fuel by a gravity feed or low pressure, and discharge itself in liquid form at the burner proper without flashing off at the point of its discharge, thus enabling the fuel to spread evenly and accommodate itself ready to be 25 acted upon in the burner in a proper way so that the gases of vaporization will become uniformly mixed with the incoming air required for combustion.

With the foregoing and other objects in view, which will be made manifest in the following detailed description and specifically pointed out in the appended claims, reference is had to the accompanying drawing for an 30 illustrative embodiment of the invention, wherein:

Fig. 1 is a perspective view of a wood burning heating stove to which the improved liquid fuel burner is shown as having been applied.

45 Fig. 2 is a vertical section through the burner.

Fig. 3 is a top plan view of the burner.

Referring to the accompanying drawing, wherein similar reference characters designate similar parts throughout, the stove illus-

trated at 10 in Fig. 1, and having the flue 11, may be of any conventional construction and as the improved burner is to be used upon various heating appliances it will be readily understood that this stove is shown for purposes of illustration only and that the use of the improved burner is not limited thereto.

55 The burner comprises a receptacle having a bottom 12, a front wall 13, a rear wall 14, and side walls 15 and 16. In the preferred form of construction the front wall 13 is much higher than the rear wall 14 and the top edges of the side walls 15 and 16 to slope downwardly toward the rear wall. This receptacle is preferably formed of cast iron, 60 fire clay, or equivalent material, and may be supported in the stove as by fire brick 17, or other refractory material. The bottom 12 has a raised central portion indicated at 18, this 65 preferably being in the form of a square pyramid having upwardly converging sides 19. In the front wall 13 near the top thereof there is formed a large air opening 20 which is surrounded by a nipple 21 adapted to be 70 caused to register with the air inlet, usually provided in the front of a wood burning stove. It will be readily appreciated, however, that if a burner is desired for use on other constructions, that the air inlet may be 75 so arranged as to enable the burner to be 80 properly accommodated thereto.

Immediately above the air inlet 20 there is 85 formed an aperture 23 to which a supply pipe 24, having a valve 25, is adapted to be connected. This supply pipe is adapted to deliver oil or liquid fluid to the burner from a suitable source of supply, such as an elevated reservoir, so that the oil may flow to the burner by gravity. An inclined baffle plate 26 extends downwardly and rearwardly from the front wall 13 and projects over the raised central portion 18 of the bottom 12. This baffle plate extends downwardly over the air inlet 20 and is preferably provided with one 90 or more transverse ridges or beads 27. The baffle plate and beads extend from side to side of the receptacle.

95 The operation and advantages of the improved burner are as follows: The oil or liquid fuel on leaving the supply pipe is dis-

charged upon the baffle 26 and is caused to flow downwardly thereover in a thin film. The ridges or beads 27 retard the flow of oil to such an extent as to assist in causing the oil to be dispersed over the baffle and flow in the thin film. Any excess oil which should not be vaporized on the baffle 26 drops from it onto the raised central portion 18 which, being relatively hot, will cause the vaporization of the oil to be completed. In many instances the amount of oil which drips down onto the forward side of the raised square pyramid is considerable. The raised central portion being relatively hot assists materially in vaporizing the oil and as the oil flows downwardly and forwardly on the pyramid, it collects at the base of the pyramid. The baffle 26 also serves to direct the incoming air downwardly, causing it to sweep downwardly near the bottom of the receptacle and pick up the vaporized fuel which results from some of the fuel having dripped off of the baffle. This downwardly directed incoming air is directed against the forward side of the pyramid on which oil is being vaporized. This forward side of the pyramid acts slightly as an obstruction for the incoming air so that the air will be caused to pick up the vapor. The air then sweeps by the sides of the pyramid or between the pyramid and the side walls 15 and 16, picking up vaporized oil which may have collected from flowing off of the forward side of the pyramid. Most of the combustion takes place near the back of the pyramid in such a manner that a strong continuous draft is automatically produced, causing a continual supply of air to be drawn in through air inlet 20. By virtue of the fact that the air inlet is located very close to the oil inlet, the oil inlet will be kept sufficiently cool to prevent the carbonizing of the fuel and the consequent clogging up of the fuel oil supply pipe.

If wood or other fuel is burned in the stove, either alone or in conjunction with the oil, the depressions or recesses around the elevated central portion of the receptacle will receive the excess of ash, the remainder of the ash being swept out of the flue by the current of air entering the receptacle and caused to sweep near the bottom by the baffle 26.

From the above described construction it will be appreciated that a novel, simple, efficient and advantageous burner is provided for handling liquid fuels, which may be easily and quickly installed in heating appliances to convert them from a wood or coal burning appliance to an oil or liquid fuel burning construction. The improved burner provides two different vaporization localities, the first being on the baffle plate 26 and the second being on the elevated central portion 18 of the bottom 12. The arrangement is such that the supply pipe is

kept relatively cool and the baffle not only serves to spread the oil in a thin film but also serves to direct the flow of air in the desired manner.

Various changes may be made in the details of construction without departing from the spirit or scope of the invention as defined by the appended claims.

I claim:

1. An oil burner comprising means providing an open topped receptacle having front, back and side walls, said receptacle having a bottom with a raised central portion in the form of a square pyramid, a baffle plate extending downwardly and rearwardly from the front wall to a point over the forward side of the square pyramid, means for discharging liquid fuel on the upper side of the baffle plate so as to trickle down over it and fall onto the forward side of the square pyramid, there being provision for admitting air to the receptacle beneath the baffle plate so as to be directed downwardly thereby against the forward side of the pyramid to pick up the vaporized fuel and then sweep rearwardly along the sides of the pyramid.

2. An oil burner for boiler furnaces, wood stoves and the like comprising means providing a bottom, front and side walls, there being an air inlet in the front wall, a baffle extending downwardly and rearwardly from the front wall above the air inlet, means for discharging oil onto the top of said baffle, means providing an upwardly and rearwardly extending surface on the bottom beneath the baffle, said surface having its sides spaced from said side walls, and means providing side surfaces at the sides of the mentioned surface which converge upwardly and which are spaced from the side walls.

In testimony whereof I have signed my name to this specification.

CHARLES E. BEYER.
